Inventor:

Owen D. McFarland
By *Tonee Rain Shingle Co.*

UNITED STATES PATENT OFFICE.

OWEN D. McFARLAND, OF CHICAGO, ILLINOIS, ASSIGNOR OF ONE-HALF TO HARRY A. CUMFER, OF CHICAGO, ILLINOIS.

SHINGLE.

Application filed December 5, 1921. Serial No. 519,986.

To all whom it may concern:

Be it known that I, OWEN D. McFARLAND, a citizen of the United States, residing at Chicago, in the county of Cook and State 5 of Illinois, have invented certain new and useful Improvements in Shingles, of which the following is a specification.

This invention relates to improvements in shingles.

10 One of the objects of the invention is to provide an improved shingle.

Another object is to provide a shingle bearing on its surface a visible guide for indicating the positions of other adjacent

15 shingles.

Another object is to provide a shingle which bears on its face a stripe of color contrasting with that of its exposed butt or body and which serves as a guide and is 20 visible between the side edges of adjacent shingles in a given course to accentuate the separation between the shingles and to increase the apparent thickness of the shingles.

Another object is to provide a guide, of 25 the character and for the purpose described, of such nature that its intended purpose is not disturbed by exposing either end of the shingle to the weather.

Another object is to provide a shingle having 30 the improved guide or guides upon both of its sides so that either of its sides may be exposed to the weather without loss of time in laying the shingles on a roof.

Another object of the invention is to provide 35 a shingle having a fire-resistant covering or facing, such as slate or other divided mineral, of different colors on opposite sides, and each side bearing the guide or suitably placed stripes or kerfs.

40 Another object is to provide a shingle bearing on its face the improved guide and visible indications locating the points for insertion of the nails.

Another object is to provide a shingle having 45 on or in its face a stripe or kerf of contrasting color, which originates and terminates in the face of the shingle, to serve as a guide for laying the shingle on the roof.

Other objects and advantages of the in- 50 vention will hereinafter appear.

In the drawings:—

Fig. 1 shows a roof made of my improved shingles as it appears when laid.

Fig. 2 shows a plan view of the shingles of which the roof is made.

55

Fig. 3 is a modification.

Fig. 4 is another modification.

Fig. 5 is a section taken on line 5—5 of Fig. 3 when the stripe or kerf is impressed in the body part of the shingle.

60

The shingle 10, consists in one of its forms, of the body part saturated with a waterproof material, such as asphalt or the like, and overlaid by fire-resistant divided material, such as slate or other mineral matter, to give the coating or surface of the shingle a desired color. The opposite side of the shingle may, or may not, be coated with similar material, of a different color. One side may be colored red and the other 70 green, for example, so that a variety of effects may be produced in the roof by the use of the single shingles in exposing either one or the other side of the shingles to view, or the bottom surface of the shingle may 75 remain uncoated with slate.

The shingle is provided with one or more black stripes or kerfs 11 extending parallel with the longest axis of the shingle and suitably spaced apart. The shingle 10^a may have one kerf 11, while the shingle 10 is provided with two kerfs or stripes serving as guides for placing the shingles upon a roof and in Fig. 4, 10^b may have two kerfs 11 located closer together than those shown in Fig. 2. The kerf or indicating guides 11 are preferably black and made on the shingle either by painting or by submerging the colored slate coating into the underlying layer of asphalt, thereby providing a 80 kerf in the face of the shingle which serves substantially the same purpose. When the shingles are laid upon the roof, after the first course, the edge 12 of the shingle 10 is laid parallel with the adjoining edge of 85 the kerf 11 of the adjoining shingle, as at 13, and the kerf 11 appears between the edges 14 and 15 of the subsequent-adjacent course. The companion kerf or stripe 11^b, shown in Fig. 1, is overlain by a shingle 90 of the subsequently laid course, so that only one of the stripes or guides 11 is shown.

When the structure shown in Fig. 2 is used the lap of the overlying course appears at 95 one side of the transverse center of the 100 shingle, whereas if Fig. 3 be employed the 105

lap will always occur in the center of the shingle, and if the structure shown in Fig. 4 is employed the lap will occur at a point nearer the center than when the shingle shown in Fig. 2 is used. The shingles of a given course are separated a distance equal to the width of the kerf or stripe.

While I am impressing the kerfs 11 in the face of the shingle, I also indent points 10 16, preferably on opposite sides of the shingle, to indicate the place where nails are to be driven into the shingle; these points are in planes within the longitudinal limits of the kerfs, or stripes 11, so 15 that the nails will not show when the superposed course is laid.

One or more nails may be driven at the point 16 and in every instance the nails pass thru two courses of singles. By using 20 the stripes 11 as guides the shingles may more uniformly be laid on the roof without the necessity of stretching a string across the roof as guides for the lower end of the shingles.

25 It is, of course, apparent that if a strip containing a plurality of shingle-simulating parts be employed the stripes may conveniently be located on the terminal shingle that serves as a guide for laying the strips.

30 While I have herein shown a single embodiment of my invention with two modifications for the purpose of indicating generally the variations that are apparent, it will be manifest that many other modifications along the same line may be made without the necessity of specific illustration 35 within the scope of the appended claims.

Having described my invention what I claim as new and desire to secure by Letters Patent, is:—

1. A shingle having an area on its face visibly distinguishable from the face, said

area being entirely enclosed within the face surface to serve as a gage in placing the shingles of an adjacent course.

45

2. A shingle having an area on its face visibly distinguishable from the face and surrounded by the face surface to serve as a gage in placing the shingles of an adjacent course, and to accentuate the appearance of 50 separation of shingles of the same course.

3. A shingle having an outlined distinguishable, elongated area on its face terminating at both ends at a material distance from the boundary edges of the 55 shingle.

4. A shingle having a distinguishable stripe on its face located inside of and spaced from the boundary thereof.

5. A shingle having a distinguishable, 60 elongated stripe on its face, parallel with the longest axis of the shingle and located wholly within and surrounded by the face surface.

6. A shingle having a distinguishable stripe in the mid-portion of its face, wholly within the boundary of the shingle and terminating substantially equal distances from the ends of the shingle.

7. A shingle having a facing surface and 70 a stripe on its face entirely surrounded by said surface.

8. A shingle having a facing surface on both sides and a stripe on the face of each side, entirely surrounded by the surface of 75 the respective sides.

9. A shingle having a facing surface and a plurality of stripes, said stripes being parallel with the longest axis of the shingle and entirely surrounded by said facing surface.

8 In testimony whereof I hereunto subscribed my name.

OWEN D. McFARLAND.
